UNITED STATES PATENT OFFICE.

THOMAS JENNINGS McCARVER, OF OREGON CITY, OREGON.

IMPROVEMENT IN SASH-HOLDERS.

Specification forming part of Letters Patent No. 118,038, dated August 15, 1871.

To all whom it may concern:

Be it known that I, THOMAS JENNINGS McCARVER, of Oregon City, Clackamas county and State of Oregon, have invented a new and Improved Mode of Window-Fastenings; and I do hereby declare that the following is a full and exact description of the same.

My invention consists mainly of a pawl or catch provided with a bar which works in a slotted guide-plate and is encircled by a spiral spring, the pawl being so placed as to hold the sash (either the upper or lower one) in any desired position, and to securely fasten the same when closed.

To enable others to make use of my invention, I will proceed to describe its construction and operation.

The pawl or catch, as shown at *a* in the diagram, is fastened to a small plate, *f*, with a rivet or screw. The plate *f* is fastened to the sash or other thing having an up-and-down movement, the ratchet *b* being fastened to the frame, casing, or guide-strip of the window, the pawl or catch and ratchet being opposite each other.

For example, I will explain the workings of the lower or bottom sash: When the sash is down the pawl or catch *a* drops under a shoulder at the bottom of ratchet *b*, making it impossible for the sash to be raised until the pawl or catch is first withdrawn, which is easily done by a gentle upward pressure with the finger against the nib *d*

on the top of the pawl or catch. While the pawl or catch is in that position the window may be raised to the desired height, when, on removing the finger, the pawl or catch will immediately drop forward and catch on one of the ratchets, as shown at *b*, in which position the window will remain until the pawl or catch *a* is again raised by the finger. The top sash works the same as the lower one, with the exception that, when closed, the pawl or catch catches on the top of ratchet at *c*, which prevents that sash from being moved until the pawl or catch is again raised with the finger. There is a spring, *e*, encircling a bar, *i*, which is attached to the back of the pawl or catch *a*, which is intended to quicken the action of the pawl or catch, and for no other purpose. This bar works in the slotted guide or flange *f*.

What I claim as my invention, and desire to secure by Letters Patent, is—

The sash-fastener herein described, consisting of the plate *f*, pawl or catch *a* pivoted thereon and provided with nib *d*, a spring, *e*, encircling an arm or bar, *i*, working in a slotted guide-plate, *c*, and ratchet-bar *b*, all constructed and arranged in the manner specified.

THOMAS JENNINGS McCARVER.
